UNITED STATES PATENT OFFICE.

MAGNUS GROSS, OF NEW YORK, N. Y.

APPARATUS FOR MANUFACTURING GAS.

SPECIFICATION forming part of Letters Patent No. 392,553, dated November 6, 1888.

Application filed December 17, 1887. Serial No. 258,243. (No model.)

To all whom it may concern:

Be it known that I, MAGNUS GROSS, a citizen of the United States, residing at New York, in the county of New York and State of New York, have invented certain new and useful Improvements in Steam - Superheaters for Making Gas; and I do hereby declare the following to be a full, clear, and exact description of the invention, such as will enable others skilled in the art to which it appertains to make and use the same.

My invention relates to the manufacture of illuminating and heating gas in which highly-heated steam is employed.

15 The object is to produce apparatus for re-heating or superheating steam or vapor which shall be of simple and inexpensive construction; which shall be free from exposure to surroundings tending to lower temperature; 20 which shall economize heat and conserve the heat of the steam, preventing loss thereof; which shall present the steam to its point of use in the proper condition of heat, and which shall, generally, be highly efficient in use.

25 With these objects in view my invention resides in a steam-superheater consisting of a chamber to be heated, a vessel or muffle in this chamber closed at one end and open at the other, and containing a pipe to be supplied 30 with steam, and a second chamber formed upon the first, the open end of the vessel or muffle in the first chamber communicating with the second chamber.

The invention consists, furthermore, in the 35 combination, with a casing forming a chamber provided with a heating device and inclosing a gas-retort or gas-retorts, and a vessel or muffle containing a steam-pipe and open at one end, of a mantle, jacket, or hood forming a 40 second chamber against the casing over the open end of the vessel or muffle held therein, the steam-pipe entering the vessel or muffle through the second chamber and passing out of it into the same; and, finally, the invention 45 consists in certain details of construction hereinafter fully set forth and claimed.

The particular construction of the plant for the distribution of the superheated steam—also shown in the drawings in this case—is not 50 herein specifically claimed, since the same forms the subject-matter of another applica-

tion for patent, one filed of even date here-with and numbered 258,244.

In the accompanying drawings, forming part of this specification, and in which like letters of reference indicate corresponding parts, Figure 1 is a front end elevation of the improvement as applied to the furnace with the jacket, mantle, or hood removed. Fig. 2 is a sectional side elevation of the same, taken 60 on the line *x x* of Fig. 1. Fig. 3 is a sectional end elevation of the improvement, taken on the line *y y* of Fig. 2.

In the manufacture of gas I prefer to place several benches, A, of any approved construc- 65 tion, into one casing, B, of masonry. Each bench A is here shown provided with the usual furnace, C, for generating heat to heat the gas-generating retorts D, of which I place usually six in every bench, so that the entire casing, 70 as shown, contains eighteen. Within the casing B is placed a vessel or muffle, E, which is closed at one end and opens at its other end into a chamber, F, formed by a jacket, mantle, or hood, G, held on one end of the casing B, 75 and being of any approved construction. The mouth-pieces H, secured at one end of the gas-generating retorts D, project a short distance through this mantle, jacket, or hood G, as shown in Fig. 2. The steam-inlet pipe I passes 80 through the mantle, jacket, or hood G, and extends into the space F to the open end of the vessel or muffle E. The pipe I here connects with a set of parallel return-pipes or coil of pipe, J, placed inside of the vessel or muffle 85 E, and the other end of the coil passes into the hood and connects with a test-pipe, K, ex-tending downward within the hood, and then out of the same, provided with a cock and serv-ing to test the quality or condition of the steam. 90

It will be seen that the heat generated in the furnaces C not only heats the gas-distilling retorts D, but also the vessel or muffle E and the chamber F, so that the steam, after passing through the inlet-pipe I, is not exposed to sur-roundings of a low temperature. As the pipes are located in the highly-heated chamber F, the superheated steam loses none of its units of heat, and is consequently very efficient for generating the gas when mixed with the va-pors of hydrocarbons or with suitable gas or vapors from other source and passed through 95 100

the heated retorts D. The heat in the vessel or muffle E can circulate from its open end into the chamber F.

This superheater may be connected up in any suitable manner—say as follows: The other end of the coil of pipe J, which is likewise at the open end of the vessel or muffle E, connects by a short pipe, L, with a distributing-pipe, N, extending horizontally along the chamber F above the top rows of the gas-retorts D. From the said distributing-pipe also extend downward the superheated-steam-supply pipes O, which furnish the necessary superheated steam for each retort D. The pipes O enter through one side of the mouth-pieces H, and then connect with any suitable mixing and injecting apparatus, in the usual manner, preferably with a mixing and injecting apparatus forming the subject-matter of an application for patent filed of even date herewith and numbered 258,246. An oil-supply pipe, also here shown as connected with the retorts, enters the mouth-piece H outside of the jacket, mantle, or hood G.

Having thus fully described my invention, what I claim as new, and desire to secure by Letters Patent, is—

1. A steam-superheater consisting of a chamber and means for heating the same, a vessel or muffle in this chamber closed at one end and open at the other and containing a pipe to be supplied with steam, and a second chamber formed upon the first, the open end of the vessel or muffle in the first chamber communicating with the second chamber, substantially as described.

2. The combination, with a casing forming

a chamber provided with a heating device and inclosing a gas-retort or gas-retorts, and a vessel or muffle containing a steam-pipe and open at one end, of a mantle, jacket, or hood forming a second chamber against the casing over the open end of the vessel or muffle held therein, the steam-pipe entering the vessel or muffle through the second chamber and passing out of it into the same, substantially as and for the purpose described.

3. The combination of the casing B, forming the chamber, with the mantle, jacket, or hood G, forming a second chamber upon the first, the first chamber being provided with a furnace, C, and holding and covering the bodies of retorts D, and containing an open-ended vessel or muffle, E, supplied with a steam-pipe or steam-pipes, and the second chamber covering or nearly covering the mouth-pieces of the retorts D and the open end of the vessel or muffle E, and also protecting the steam-inlet pipe and the discharge-pipe and connections, substantially as described.

4. The combination, with the casing B, provided with means for heating it and forming a chamber, and mantle or hood G, forming a second chamber upon this, of the vessel or muffle E, closed in the first chamber, but opening into the second, and containing a steam-pipe, the inlet and discharge ends of which are in the second chamber, the discharge end being supplied with a test-pipe, N, substantially as set forth.

MAGNUS GROSS.
